CLAIM

The ornamental design for a RV level block, as shown and described.

DESCRIPTION

FIG. 1 is a bottom view of the RV level block;

FIG. 2 is a bottom perspective view thereof;

FIG. 3 is a top view thereof;

FIG. 4 is a left side view thereof;

FIG. 5 is a right side view thereof;

FIG. 6 is a back view thereof; and,

FIG. 7 is a front view thereof.

The broken lines illustrate portions of the RV level block in which the design is embodied and forms no part of the claimed design.
